FINNED TIP EXTENSION BAR FOR AN OXY-GAS TORCH

John P. Broderick, Bayside, N.Y., assignor to Eutectic
Welding Alloys Corporation, a corporation of New
York

Filed Nov. 10, 1964, Ser. No. 82,539

Term of patent 14 years

(Cl. D62—2)

FIG. 1 is a perspective view of a finned tip extension bar for oxy-gas torch showing my new design;

FIG. 2 is a side elevational view thereof;

FIG. 3 is a front elevational view thereof; and

FIG. 4 is a top plan view thereof.

I claim:

The ornamental design for a finned tip extension bar for an oxy-gas torch, as shown.
